UNITED STATES PATENT OFFICE.

FRANK CRIMI, OF HOLYOKE, MASSACHUSETTS.

HAT-RETAINING DEVICE.

No. 833,585.

Specification of Letters Patent.

Patented Oct. 16, 1906.

Application filed June 14, 1906. Serial No. 321,732.

To all whom it may concern:

Be it known that I, FRANK CRIMI, a citizen of the United States of America, and a resident of Holyoke, in the county of Hampden 5 and State of Massachusetts, have invented certain new and useful Improvements in Hat-Retaining Devices, of which the following is a full, clear, and exact description.

This invention relates to an improved device for the retention of hats upon the heads of persons; and it consists in a device of the character described of a supporting member having means for its attachment to and to depend below, the rim of the hat adjacent the 15 hat side, a screw threading horizontally through and longitudinally movable relatively to the supporting member below the rim and having a head bearing-piece at its inner end.

20 The invention furthermore consists in certain features of construction embodied in the device, which are hereinafter referred to and described, and for the attainment of advantages which will be set forth.

25 The device is illustrated in the accompanying drawings, in which—

Figure 1 is a view showing the retaining device as applied on a hat and in use. Fig. 2 is a substantially central vertical sectional 30 view through the device. Fig. 3 is a horizontal sectional view of the same as taken on the line 3-3, Fig. 2.

Similar characters of reference indicate corresponding parts in all of the views.

35 In the drawings, *a* indicates the supporting member of the device, having a screw-hole *b* horizontally therethrough and having thereabove a horizontal shoulder *d* and an upstanding screw-threaded stud *f*, provided with

40 a pointed hat-piercing extremity *f*². The pointed stud may be forced upwardly through the felt or other material forming the rim portion of the hat near the hat side, rendering it unnecessary to employ an eyelet-hole 45 punch or other implement, and the clamping-nut *g* screw-engages the upwardly-protruding portion of said stud and clamps against the upper side of the hat-rim, binding the portion thereof adjacent the hole pierced by the

50 pointed end of the stud firmly against the underlying shoulder *d*. The clamping-nut *g* is made with a closed end *g*², so that the pointed end of the stud is concealed and protected. The screw *h*, provided with a head *h*² at its 55 outer end, has intermediately of its length a screw engagement through the horizontal

screw-hole *b* of the depending supporting member *a*, and the screw carries at its inner end a head bearing-piece *B*, relatively to which the screw may freely rotate without 60 turning the piece *B*, said head bearing-piece and screw being, however, bodily movable in unison in the direction of the length of the screw. The endwise movement of the screw is, as apparent, acquired by rotating the screw 65 so that the same adjusts the head bearing-piece inwardly to tighten against the side of the head or outwardly for its withdrawal from such engagement.

The head bearing-piece comprises a block *i* 70 of metal or other suitable material and has on its inner face a section *j* of compressible material, such as rubber or felt, to make a cushion. As shown, the swiveling engagement between the inner extremity of the screw and the head bearing-piece is accomplished by 75 forming the metallic section *i* with a countersunk hole *k* therethrough, forming or providing the screw with a shoulder *m* near its inner end, and having the extremity *n* of the screw 80 inserted axially through the countersunk hole *k*, and providing a washer *o* in the portion of the countersunk hole *k* of the larger diameter, and upsetting, as indicated at *p*, the end of the screw adjacent and to overlap the external face of the washer. The layer *j* of rubber 85 or other cushioning material covers the joint.

As apparent and in a manner stated, the device includes means whereby one is enabled to conveniently form a hole in the hat- 90 rim for the introduction therethrough of the stud, and the clamping-nut in conjunction with the shoulder thereunder reinforces the hat-rim around the margin of the hole therethrough, so that the necessity of a reinforcing-eyelet at this place is avoided. 95

The device, preferably located at the side of the hat and having the most bulky portion thereof located closely under the rim, is practically out of sight and unobjectionable, 100 so far as appearances are concerned, and in the binding operation of the device the hat is crowded to a hard bearing against the head at one side, leaving a space between the head and the hat side adjacent the location of the 105 retaining attachment, with the result of giving a good ventilation within the hat, as apparent from Fig. 1 of the drawings, and the hat being bound to the head at the side, or, if preferred, at the back, obviates the creasing 110 or marking of the forehead of the wearer, as commonly observed where hats are worn

with sufficient closeness of fit to keep them securely on the head. When it is windy and under other circumstances, a person may readily adjust the screw to set the head bearing-piece to have its not uncomfortable bind against the side of the head with absolute assurance that the hat will remain securely in place, and the device may be manipulated to free the engagement of the retainer when there is no necessity therefor, and the device may be most readily detached when desired.

I claim—

1. In a hat-retaining device, a supporting member having means for its attachment to, and to depend below, the rim of the hat adjacent the hat side, a screw, threading horizontally through, and longitudinally movable relatively to, the supporting member below the rim, and having a head bearing-piece at its inner end.
2. In a hat-retaining device, a supporting member having means for its attachment to, and to depend below the rim of the hat adjacent the hat side, a screw threading horizontally through, and longitudinally movable relatively to, the supporting member below the rim, and having a head bearing-piece at its inner end relatively to which the screw is rotatable, but movable bodily in unison with the endwise movement of the screw.
3. In a hat-retaining device, a supporting member having means for its attachment to, and to depend below the rim of the hat adjacent the hat side, a screw threading horizontally through, and longitudinally movable relatively to, the supporting member below the rim, and having a head bearing-piece at its inner end relatively to which the screw is

rotatable, but movable bodily in unison with the endwise movement of the screw, and said head bearing-piece having at its inner side a portion of compressible material.

4. In a hat-retaining device, a supporting member having a horizontal screw-threaded hole therethrough, and comprising thereabove an upstanding screw-stud, a screw, threading horizontally through, and longitudinally movable relatively to, the supporting member, and having a head bearing-piece at its inner end; and a clamping-nut for engagement with said upstanding stud.

5. In a hat-retaining device, a supporting member having a screw-hole horizontally therethrough, and having thereabove a horizontal shoulder and an upstanding screw-threaded stud provided with a pointed, hat-piercing, extremity, a clamping-nut to screw-engage said stud and inclose the pointed upper end thereof, a screw, having a head at its outer end, having intermediately of its length a screw engagement through said horizontal hole of the supporting member, and carrying a head bearing-piece at its inner end relatively to which the screw may rotate, said piece and screw being however bodily movable in unison in the direction of the length of the screw, and said head bearing-piece having a cushion at its inner side.

Signed by me at Springfield, Massachusetts, in presence of two subscribing witnesses.

FRANK CRIMI.
